G. E. JONES.

FOLDING MACHINE.

No. 247,922.

Patented Oct. 4, 1881.

UNITED STATES PATENT OFFICE.

GILBERT E. JONES, OF NEW YORK, N. Y.

FOLDING-MACHINE.

SPECIFICATION forming part of Letters Patent No. 247,922, dated October 4, 1881.

Application filed July 12, 1881. (No model.)

To all whom it may concern:

Be it known that I, GILBERT E. JONES, a citizen of the United States, residing at New York, in the county and State of New York, have invented new and useful Improvements 5 in Folding-Machines, of which the following is a specification.

This invention relates to a folding-machine which is intended particularly to impart longitudinal folds to a web or sheets passing through it; and the invention consists, principally, in the construction of the folder, and in various combinations of the same with other devices, all of which are particularly hereinafter set forth.

This invention is illustrated in the accompanying drawings, in which Figure 1 represents a plan or top view of a machine embodying my invention. Fig. 2 is a longitudinal vertical section of the same. Fig. 3 is a side view of one pair of converging half-twist tapes detached. Fig. 3* is a detached view of the rollers and a portion of one pair of the converging half-twist tapes. Fig. 4 is an end view of the machine. Figs. 5 and 6 are details, which 25 will be referred to as the description progresses.

Similar letters indicate corresponding parts.

In the drawings, the letters A A' designate two rollers which feed the sheet to be folded into the folding-machine. As the sheet leaves 30 these feed-rollers its central portion is caught between the creasing-rollers B B', and its edges pass between the tapes C C' D D'. The tapes C C' are situated on one side of the machine. They are stretched over pulleys c c' c' c'', respectively, the pulleys c c' being mounted on horizontal axles c⁴ c⁵ (see Fig. 3) close to the feed-rollers A A', while the pulleys c' c'' are mounted on vertical axles c⁶ c⁷ (Figs. 1 and 4) secured in a traverse, E, at the outer end of the main 40 frame F. The tapes D D' are situated on the opposite side of the machine, and they are stretched over pulleys d d' d' d'', respectively, the pulleys d' d'' being mounted on horizontal axles close to the feed-rollers A A', while the 45 pulleys d² d³ are mounted on vertical axles d⁶ d'', Figs. 1 and 4, secured to the traverse E.

By referring to Figs. 1, 2, and 3 it will be seen that each of the tapes C C' D D' has a half-twist, and, furthermore, the two pairs of

tapes converge toward the outer end of the 50 machine. At the point where the edges of the sheet pass from the feed-rollers between the tapes C C' and D D', respectively, said tapes are in horizontal planes, but as these tapes gradually turn from a horizontal to a vertical 55 position the edges of the sheet are compelled to follow, and they assume a vertical position as they approach the outer end of the machine. At the same time the central part of the sheet, after having been carried through between the 60 creasing-rollers B B', passes beneath a cord, e, which is stretched over pulleys e' e'', Figs. 1 and 2, in a downwardly-inclined position, (best seen in Fig. 2,) the central portion or bight of the sheet being supported by guide-rollers f f'. 65 By the co-operation of the creasing-rollers B B', half-twist converging tapes C C' D D', and downwardly-inclined cord e, the sheet is gradually folded, and as it approaches in its partially-folded condition the outer end of the 70 machine its sides or wings strike the secondary tapes G H, which are stretched over vertical rollers g g' h h', Figs. 1, 2, and 4. By referring to these figures it will be seen that the rollers g and h are mounted on opposite sides of the 75 main frame F in lugs or brackets g² h², respectively, while the rollers g' h' are mounted in the outer end of the main frame F, in brackets g³ h³ and traverse i, (see Fig. 4,) the roller g' being 80 directly beneath the pulley c², and the roller h' directly beneath the pulley d². The lower ends of the rollers g' h' are enlarged, (see Figs. 2 and 4,) and by the action of the secondary tapes G H the partially-folded sheet is carried between the rollers g' h', the bight of the sheet 85 being firmly compressed by the enlarged portions of said rollers. The sheet, having been folded in a longitudinal direction, is delivered by the rollers g' h' to an additional folding 90 mechanism, I, which may be such as described in Letters Patent No. 229,419, granted to me June 29, 1880, or of any other suitable construction to impart to the sheet an additional fold in the direction at right angles to that produced by the folding mechanism above described. 95

In order to produce the longitudinal fold it is not absolutely essential to employ both the

cord *e* and creasing-roller, since by using the cord *e* without the creasing-roller the sheet will be folded, and in the same manner a fold may be produced by using the creasing-rollers without the cord *e*. The essential and chief elements in my folding-machine are the half-twist converging tapes.

It remains to indicate the means by which I impart motion to the various working parts of my folding-machine.

The feed-rollers *A A'* receive their motion from the printing-press, if my folding-machine is used in connection with such, or said rollers may receive their motion by any suitable means.

15 The pulleys *c c' d d'*, which carry the half-twist converging tapes *C C' D D'*, are driven by frictional contact from the feed-rollers *A A'*. For this purpose cone-pulleys *m* are employed, Figs. 1 and 2, which are mounted on shaft *n*, running parallel to the shafts of the pulleys *c c' d d'*, respectively, and which bear against one of the feed-rollers, *A* or *A'*, and against corresponding cone-pulleys, *o*, mounted on the shafts of the pulleys *c c' d d'*, respectively.

25 The creasing-roller *B* is driven by frictional contact from the upperfeed-roller, *A*. For this purpose a friction-pulley, *p*, is mounted on a shaft, *p'*, and brought in contact with the feed-roller *A*, and with a friction-pulley, *p²*, Figs. 1 and 6, mounted on the shaft of the creasing-roller *B*. (See Figs. 1 and 5.) On the shaft of the creasing-roller *B* is also mounted a friction-pulley, *q*, Figs. 1 and 6, which, by means of an intermediate friction-pulley, *q'*, imparts motion to a friction-pulley, *q²*, Fig. 1, mounted on the shaft of the pulley *c'*, which carries the cord *e*.

The secondary tapes *G H* receive their motion from the pulley *d³*, Fig. 4, the shaft of which extends down and carries a cog-wheel, 40 *r*, which meshes in a cog-wheel, *r'*, mounted on the shaft of the roller *h'*, and gearing into a similar cog-wheel, *r²*, mounted on the shaft of the roller *g'*.

In conclusion, I will remark that the effect of 45 my folder will be the same if the cord *e* runs in an upwardly-inclined direction instead of in a downwardly-inclined direction, provided the position of the secondary tapes and other parts is changed to correspond.

50 What I claim as new, and desire to secure by Letters Patent, is—

1. The combination of the feed-rollers, the half-twist converging tapes, and means, substantially such as described, for acting on the 55 central portion of the sheet to aid in forming the longitudinal fold.

2. The combination of the feed-rollers, the half-twist converging tapes, means, substantially such as described, for acting on the central portion of the sheet to aid in forming the

longitudinal fold, and the secondary tapes *G* and *H*, essentially as set forth.

3. The combination, substantially as hereinbefore described, of the feed-rollers, the half-twist converging tapes, and the cord *e*. 65

4. The combination, substantially as hereinbefore described, of the feed-rollers, the creasing-rollers, the half-twist converging tapes, and the cord *e*.

5. The combination, substantially as hereinbefore described, of the feed-rollers, the creasing-rollers, the half-twist converging tapes, the cord *e*, and the supporting-rollers *f*. 70

6. The combination, substantially as hereinbefore described, of the feed-rollers, the creasing-rollers, the half-twist converging tapes, the cord *e*, and the secondary tapes *G H*. 75

7. The combination of the feed-rollers, the half-twist converging tapes, means, substantially such as described, for acting on the central portion of the sheet to aid in forming the longitudinal fold, the secondary tapes *G* and *H*, and the pressing-rollers *g'* and *h'*, essentially as set forth. 80

8. The combination, substantially as hereinbefore described, of the feed-rollers, the creasing-rollers, the half-twist converging tapes, the cord *e*, the secondary tapes *G H*, and the pressing-rollers *g'* *h'*. 85

9. The combination, substantially as hereinbefore described, of the feed-rollers, the creasing-rollers, the half-twist converging tapes, the cord *e*, the supporting-rollers *f*, the secondary tapes *G H*, and the pressing-rollers *g'* *h'*. 90

10. The combination of the feed-rollers, the half-twist converging tapes, and the friction-pulleys *m* and *o* for imparting motion to the tapes. 95

11. The combination, substantially as hereinbefore described, of the feed-rollers, the half-twist converging tapes, the creasing-rollers, the cord *e*, the friction-pulleys *p p²*, for imparting motion to the creasing-rollers, and the friction-pulleys *q q' q²*, for imparting motion to the cord *e*. 100

12. The combination of the feed-rollers, the half-twist converging tapes, means, substantially such as described, for acting on the central portion of the sheet to aid in forming the longitudinal fold, the secondary tapes *G* and *H*, the pulley *d³*, the shaft *d³*, the pressing-rollers *g'* and *h'*, and cog-wheels *r r' r²*, essentially as set forth. 110

In testimony whereof I have hereunto set my hand and seal in the presence of two sub- 115 scribing witnesses.
